CIGARETTE LIGHTER

Harry Negbaur, New York, N. Y., assignor to
H. Negbaur & Co., New York, N. Y., a copartnership

Application August 20, 1948, Serial No. 148,202

Term of patent 7 years

(Cl. D48—27)

To all whom it may concern:

Be it known that I, Harry Negbaur, a citizen of the United States of America and a resident of New York, in the county of New York and State of New York, have invented a new, original, and ornamental Design for a Cigarette Lighter, of which the following is a specification, reference being had to the accompanying drawing, forming a part thereof.

In this drawing:

Figures 2, 3 and 4 are front elevational, side elevational and rear elevational views respectively of the same; and

I claim:

The ornamental design for a cigarette lighter, as shown.

HARRY NEGBAUR.
